(57) **CLAIM**

The ornamental design for a wire storage, as shown and described.

DESCRIPTION

FIG. 1 is a first perspective view of a wire storage showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a third perspective view showing the wire storage, in closed state.

The broken lines shown in the drawings depict portions of the wire storage that form no part of the claimed design.
